US00D615339S

(12) **United States Design Patent**
Bronwasser

(10) **Patent No.:** **US D615,339 S**
(45) **Date of Patent:** **** May 11, 2010**

(54) **BEVERAGE PREPARATION DEVICE**

(75) Inventor: **Robert Wim Bronwasser**, Amsterdam
(NL)

(73) Assignee: **Conopco Inc.**, Englewood Cliffs, NJ
(US)

(**) Term: **14 Years**

(21) Appl. No.: **29/340,529**

(22) Filed: **Jul. 21, 2009**

(30) **Foreign Application Priority Data**

Jan. 24, 2009 (GB) 4010032

(51) **LOC (9) Cl.** **07-01**

(52) **U.S. Cl.** **D7/306**; D7/309; D7/311

(58) **Field of Classification Search** D7/306-311,
D7/378, 379; 99/282, 280, 285

See application file for complete search history.
